[57] CLAIM

The ornamental design for a night light with simulative radar detector base or the like, as shown and described.

DESCRIPTION

FIG. 1 is a front elevational view of a night light with simulative radar detector base or the like, showing my ornamental design thereof;

FIG. 2 is a right end elevational view thereof with certain environmental structure shown in broken lines;

FIG. 3 is a back elevational view thereof with certain environmental structure shown in broken lines;

FIG. 4 is a left end elevational view thereof with certain environmental structure shown in broken lines;

FIG. 5 is a top plan view thereof with certain environmental structure shown in broken lines; and,

FIG. 6 is a bottom plan view thereof with certain environmental structure shown in broken lines.
